UNITED STATES PATENT OFFICE.

EDWIN J. MURPHY AND LEONARD P. HUTT, OF SCHENECTADY, NEW YORK, AS
SIGNORS TO GENERAL ELECTRIC COMPANY, A CORPORATION OF NEW YORK.

SEARCHLIGHT.

Original application filed May 17, 1920, Serial No. 381,904. Divided and this application filed December 19, 1924. Serial No. 757,002.

This application is a division of our pending application, Serial No. 381,904, filed May 17, 1920.

Our invention relates to electromagnetic means, and more in particular it relates to electromagnetic means that are especially adapted for use in connection with an arc lamp making it possible to secure reliable automatic control of the electrodes. The 10 electromagnetic device of our invention is adapted also to control the striking of the arc by causing the negative electrode to be separated from the positive electrode and also to control the feeding operations of the 15 negative electrode as will more fully appear.

The invention will be readily understood by referring to the accompanying drawing in which Fig. 1 is a diagrammatic illustration of the circuits used in connection with the arc of our prior application and of the electromagnetic device of our invention; Fig. 2 is a side view of the electromagnetic device.

25 In the arc lamp disclosed in our said prior application when the current is turned off the electrodes are left in contact and when the current is turned on the arc is struck by withdrawing the negative electrode a suitable distance.

30 In the said prior application a feeding mechanism is provided through the medium of which the negative electrode may be fed toward the positive electrode to compensate for the consumption due to the arc or the 35 negative electrode may be backed away from the positive electrode in case the distance between the electrodes has been reduced more than the proper amount.

40 The mechanism for accomplishing these feeding operations is under the control of a pair of solenoids 139 and 143, Fig. 1. Each of these solenoids is provided with a core which is slidably keyed upon a driving shaft, 45 not shown. As shown, the solenoid 139 is provided with a core 138 and the solenoid 143 is provided with a core 142. The core 138 is provided in turn with a driving cone 144, while the core 142 is provided with a 50 similar driving cone 145. Between these cones there is provided a cone 146 which is adapted to be driven by either of the cones 144 or 145 depending upon which one of the solenoids is energized, the driving cones be-

ing normally kept out of engagement with the cone 146 by suitable coiled springs. By this arrangement the cone 146 may be rotated either backwards or forward with the result that the negative electrode 97 may be fed either forward or backward.

The arrangement of this device is such that when neither of the solenoids is energized the cone 146 is not driven and consequently the electrode 97 is not fed.

55 By means of the electromagnetic device of our invention the solenoids 139 and 143 are automatically controlled to maintain the negative electrode in its proper position in order that the arc may be maintained in a constant condition. The control of the two 60 solenoids is accomplished through the medium of the armature 156 of the electromagnetic device. Furthermore, through the medium of the armature 152 of the same device the arc is drawn between the electrodes 97 and 70 25 when the current is turned on through the lamp.

A more detailed description of the invention follows: The arc is started by energizing the electromagnet 148 which is in series 80 with the electrodes and receives current from the main line 149. The armature 152 carries the arm 154 (see Fig. 2) the forward end of which is pivotally joined to a length (not shown) to which length the negative electrode 97 is secured. When the electromagnet 85 148 is energized the armature 152 is attracted and consequently the negative electrode 97 is operated from the positive electrode and the arc thereby starts.

90 The electromagnetic device is provided further with the armature 156 which serves as a contact maker for controlling the solenoids 139 and 143. The magnetic circuit of the electromagnetic device passes through the core 148' attached to the L-shaped yoke 150. It also passes through the armature 152. The upper portion of the yoke consists of two cross pieces secured to the stationary base 151'. These cross pieces 150 have a 95 portion 150' turned down and cut away in order to reduce the cross section thereof. This reduced section becomes more saturated than the larger sections and produces a leakage flux which is used for operating the 100 armature 156. This armature is pivotally supported to a fixed standard 155. The forward end of the armature 156 carries a con-

tact 157 arranged to play between two fixed but adjustable contacts 158 and 159. This armature is counterbalanced by a weight 160 secured to the opposite end by means 5 of a brass strip 161.

Near the contact end of armature 156 there is pivoted an arm 162 of non-magnetic material, the arm extending backward toward the upright 155 and is at its rear end 10 turned upward and there carries a screw 163 which holds one end of the helical spring 164, the other end of which spring is secured to the standard 155. The tension of the spring can be adjusted by means of the 15 screw. It will be seen that the armature 156 is provided with a perforation in line with both the adjustable stop 165 and the fixed stop 166. The adjustable stop 165, it will be seen, is mounted on the arm 162, 20 while the fixed stop 166 is secured to the restricted portion 150' of the yoke. Another adjustable stop 167 is provided on the armature 156 in the path of the arm 162.

The fixed contacts 158 and 159 are connected with the solenoids 139 and 143 by conductors 168 and 169. At a point between the solenoids 139 and 143 along the conductor 170 a connection is made to a switch 171 through the medium of which connection is 25 made by way of contact 171' with the conductor 172 and with the negative main 149. On the other hand the armature 156 is connected by conductor 173 with the positive side of the main 149.

30 The operation of the relay system for the automatic control for the negative electrode depends upon the difference in pull upon the armature 156 by the leakage flux on the one hand and the spring 164 on the other. The 35 magnetic pull depends upon the air gap between the armature 156 and the yoke.

In working out this electromagnetic device it was found advisable to provide a small non-magnetic gap 151 between the core 40 148' and the head 151'. This prevents too high a saturation of the whole magnetic circuit and improves the sensitiveness of the 45 relay to changes in the exciting current.

When the normal current passes through 50 the lamp the armature 152 is attracted and the forces are so balanced that the contact 157 touches neither of the contacts 158 nor 55 159 and the stops 165 and 166 are in contact the arm 162 bearing upon the stop 167. The adjustable elements 157, 158, 159, 163, 60 165 and 167 are adjusted to establish this condition. Slight variations of current do not perceptibly affect the conditions of the equilibrium of the armature 156. But if the 65 current strength is reduced to a considerable degree the leakage flux is perceptibly diminished and the armature 156 promptly responds so that the spring 164 over-balances the magnetic pull to the extent that the armature 156 rises and contact 157 strikes the

fixed contact 158. By this action the stop 165 rises above stop 166 but the arm 162 continues in contact with stop 167. In this condition of the apparatus the lever 156 is in quasi-equilibrium and contact 157 is only 70 returned to its middle position when the current again rises to its normal strength.

When the current for any reason rises perceptibly above its normal strength the magnetic pull overpowers the pull of the spring 75 164 and the armature 162 descends until contact 157 strikes contact 159 and is there again in quasi-stable equilibrium. By this downward movement of lever 156 the stops 165 and 166 are maintained in contact, the latter now acting as a secondary pivot but the arm 162, pulling the spring 164 and turning about its pivot near the free end of the armature 156, is raised from stop 167.

In the operation and for the preservation 85 of the quasi-stable equilibrium of contact 157 in its three positions the directing of the axis of spring 164 is important. This axis (in the line of which the spring primarily acts) is indicated by the dotted line 90 ω , and it will be noticed that it passes above the pivot of arm 162; moreover, the direction of this axis can be adjusted by the stop 167. While the resultant course of spring 164 is in the line of its axis only a component of this force, at right angles to the axis, 95 acts upon the arm 162 to turn it about its principal and secondary pivots thus maintaining its contact with stop 167. This component increases with the angle which the axis 100 of the spring forms with the line connecting the point of central attachment of the spring on standard 155 with the pivot of arms 162 and the greater this component, the greater must be the magnetic pull on armature 156 105 to balance or to overpower the same. For this reason the contact 157 can be moved from any of its three positions because of the current through the coil 148.

It will be seen therefore that through the 110 medium of the electromagnetic device, whenever the arc becomes too elongated, the solenoid 143 comes into operation and causes the negative electrode 97 to advance and thus reduce the length of the arm. On the other 115 hand, if for any reason the arc becomes too short the increase in current through the coil 148 causes the solenoid 139 to come into play with the result that the negative electrode is withdrawn. The withdrawing operation 120 will continue until the armature 156 breaks the circuit through the solenoid 139 and the advancing operation as a result of the energization of the solenoid 143 continues until the armature 146 breaks the circuit through 125 solenoid 143. As long as the arc is of the proper length the armature 156 retains its balanced position midway between the contacts 159 and 158 and the feeding operations of the negative electrode are suspended. 130

What we claim is new and desire to secure by Letters Patent of the United States, is,—

1. A circuit reverser operating to move and hold a switch arm on open circuit and in either of two circuit closing positions in stable equilibrium, comprising an electromagnet, an armature affording a path for the leakage flux and carrying a movable electric contact, said electromagnet having a reduced core section under said armature, two contacts in the path of the movable contact, an arm pivoted to the armature, a spring exerting a pull upon the arm in a direction above its pivot, and two stops for the arm, whereby the latter is subjected to the action of the transverse components of the pull of the spring and thereby reacts upon the armature.
2. In combination, an electromagnet, an armature therefor, an arm pivoted on said armature, a stop for the arm for limiting the rotation of the arm with respect to the armature, and a stop independent of the armature for causing the rotation of the arm with respect to the armature when the armature is operated by the magnet.
3. In a circuit controlling device, a magnet, an armature for said magnet, an arm pivoted on the armature, and a resilient element for exerting a pulling force upon said armature through the medium of said arm and a pair of stops for the arm for controlling the amount of force exerted by said resilient element upon said armature through said arm.
4. In a circuit controlling device, a magnet, an armature for said magnet, an arm pivoted on the armature, and a resilient element for exerting a pulling force upon said armature through the medium of said arm, and a pair of stops for the arm for controlling the amount of force exerted by said resilient element upon said armature through said arm, one of said stops being interposed between the arm and the armature.
5. In a circuit controlling device, a magnet, an armature for said magnet, an arm pivoted on the armature, and a resilient element for exerting a pulling force upon said armature through the medium of said arm, and a pair of stops for the arm for controlling the amount of force exerted by said resilient element upon said armature through said arm, one of said stops interposed between the arm and the armature, and the other of said stops being mounted independently of said armature.
6. In a circuit controlling device, a magnet, an armature for said magnet, an arm pivoted on the armature, and a resilient element for exerting a pulling force upon said armature through the medium of said arm, and a pair of stops for the arm for controlling the amount of force exerted by said
7. In combination with a magnet, an armature for the magnet mounted to rotate about an axis, a first contact on one side of said armature, and a second contact on the other side of said armature, said contacts being located in operative relation to said armature whereby electric connection may be made to either one or the other of said contacts by the operation of the armature, an arm mounted on said armature to rotate about an axis offset from said first axis, said contacts serving also one to limit the rotation of the armature in one direction and the other to limit the rotation of the armature in the opposite direction about its axis, a stop for the arm located between the arm and the armature for limiting the rotation of the arm about its axis with respect to the armature, and a second stop mounted independently of the armature for causing rotation of the arm about its axis with respect to the armature, and a resilient element connected to said arm for exercising a pull on the armature through said arm in opposition to the pull of the magnet, said resilient element being adapted to bring the armature into engagement with the first one of said contacts when the magnet is deenergized, said magnet being adapted when energized to exert a pulling force on said armature to disengage said armature from said first contact, and to advance the armature until the two stops are brought simultaneously into operation, said stops serving to bring the armature to a standstill at a particular point between said contacts, said magnet being also adapted when energized more strongly to advance the armature beyond the intermediate stop position into engagement with the second one of said contacts.
8. In combination with a magnet, an armature for the magnet mounted to rotate about an axis, a first contact on one side of said armature, and a second contact on the other side of said armature, said contacts being located in operative relation to said armature whereby electric connection may be made to either one or the other of said contacts by the operation of the armature, an arm mounted on said armature to rotate about an axis offset from said first axis, said contacts serving also one to limit the rotation of the armature in one direction and the other to limit the rotation of the armature in the opposite direction about its axis, a stop for the arm located between the arm and the armature for limiting the rotation of the armature

the arm about its axis with respect to the armature, and a second stop mounted independently of the armature for causing rotation of the arm about its axis with respect 5 to the armature, and a resilient element connected to said arm for exercising a pull on the armature through said arm in opposition to the pull of the magnet, said resilient element being adapted to bring the armature 10 into engagement with the first one of said contacts when the magnet is deenergized, said magnet being adapted when energized to exert a pulling force on said armature to disengage said armature from said first contact, and into engagement with said second contact with said arm operative in engagement with only one of said stops, said stop serving to increase the tension between said 15 resilient element and said arm whereby when said magnet is weakened the armature is separated by said resilient element from the second contact and returns toward the intermediate position until the second stop of said arm is brought into operation, said second 20 stop serving to reduce the effective pull of the resilient element and to bring it into equilibrium with the pull of the magnet on the armature thereby insuring a stable intermediate position between said contacts for 25 the armature.

9. A circuit controller comprising an electromagnet, a pivoted armature for said magnet, a pair of contacts located one on each

side of the armature and in operative relation to the armature whereby the armature 35 may engage either one or the other of said contacts, an arm pivoted on the armature, the armature and arm forming an armature structure, the axes of the pivots being displaced with respect to each other, a spring 40 under tension secured to the arm whereby the armature and the arm may both be made to rotate about the axes of their respective pivots, a stop for the arm located on the armature structure for limiting the rotation 45 of the arm with respect to the armature and a stop for the arm mounted in operative relation to the arm and stationary with respect to the armature structure for causing the rotation of the arm about its axis, said 50 stops and said contacts being so disposed with respect to each other that, first, when the armature is in engagement with one of said contacts the arm is free from the restraining action of both stops; second, when 55 the armature is disengaged from both contacts the arm is restrained by both stops whereby the armature may be brought to a stop at a point between the two contacts; and, third, when the armature is in engagement with the second contact the arm is restrained by only one of said stops.

In witness whereof, we have hereunto set our hands this 18th day of December, 1924.

EDWIN J. MURPHY.
LEONARD P. HUTT.
